UNITED STATES PATENT OFFICE.

ELIZABETH CALKINS, OF ST. JOSEPH, MISSOURI.

HAIR CURLER.

Application filed July 25, 1922. Serial No. 577,395.

To all whom it may concern:

Be it known that I, ELIZABETH CALKINS, a citizen of the United States, and a resident of St. Joseph, in the county of Buchanan and State of Missouri, have invented a new and Improved Hair Curler, of which the following is a full, clear, and exact description.

This invention relates to improvements in hair curlers, an object of the invention being to provide a wire covered padded, or kid curler as it is known in the art, with an improved arrangement of wire projecting through the covering and having projecting looped ends which permit the ends of the curler to be bent over the hair after the latter is wound on the main portion of the curler and to prevent possibility of entangling the wire in the hair.

A further object is to provide a curler of the character stated in which the ends of the wire being projected beyond the covering are bent backwards in general loop form and close against the main portion of the wire, the extremity of the wire being enclosed in covering so that the wire will not catch in the hair, nor will the wire work through and injure the cover.

With these and other objects in view, the invention consists in certain novel features of construction and combination and arrangement of parts, as will be more fully hereinafter described and pointed out in the claims.

In the accompanying drawings—

Figure 1 is a perspective view illustrating my improved curler in operative position on the hair.

Figure 2 is a view in side elevation of the curler in flat position.

Figure 3 is an edge view or elevation of the curler taken at right angles to Figure 2.

Figure 4 is a view of the wire removed.

Figure 5 is a view in transverse section on the line 5—5, of Figure 2.

1 represents a wire which is of bendable material, and which throughout the greater portion of its length is enclosed by a covering 2, the latter being of kid, or any other suitable material having its edges secured by a line of stitching or other securing means 3.

The covering 2 may contain padding as illustrated at 4 in Figure 5, or may be variously padded, or padding may be omitted as may be desired.

The extremities of the wire 1 are bent backwardly and slightly curved, forming loops 5 which project beyond the ends of the covering as shown clearly in Figure 2, with the extreme ends of the wire bent close to the main portion of the wire so as to prevent the ends of the wire from cutting through the covering.

These looped extremities of the wire permit a ready bending of the ends of the curler over the hair after the latter has been wound on the body of the curler, as shown clearly in Figure 1, and they permit a continual or repeated bending operation without danger of injuring or entangling in the hair, and without injuring the curler.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

I claim:

1. A hair curler, comprising a single bendable wire, a cover on the main portion of the wire and having tapering ends, and the ends of the wire bent into looped form and having the looped ends projecting beyond the ends of the cover.

2. A hair curler, comprising a flexible covering, padding in the covering, a wire projecting through the covering, and looped ends on the wires projecting beyond the covering, the extremities of the wires located within the covering and close to the main portion of the wire.

3. A hair curler, comprising a cover of flexible material and having tapering ends, and a wire having loops at its ends and enclosed within the cover with the loops projecting beyond the ends of the cover, the free ends of the loops being in engagement with the body of the wire and lying within the cover.

MRS. ELIZABETH CALKINS.
